UNITED STATES PATENT OFFICE.

RALPH G. LOCKETT, OF MILWAUKEE, WISCONSIN, ASSIGNOR, BY MESNE ASSIGNMENTS, TO CUTLER-HAMMER INC., A CORPORATION OF DELAWARE.

ELECTRICAL CONTROLLER FOR CONVEYING SYSTEMS.

Application filed February 23, 1926. Serial No. 90,088.

This invention relates to electrical controllers for conveying systems and while not limited thereto, is particularly applicable to the control of pulverized fuel feeding devices for the furnaces of boilers and the like.

An object of the invention is to provide a fuel feeding system for boiler furnaces and the like wherein the amount of fuel supplied 10 is controlled automatically in accordance with the demand upon the boiler.

Another object is to provide for automatically varying in substantially equal increments or decrements the quantity of fuel 15 supplied to the furnace, throughout the total range of variation in the fuel supply.

Another object is to provide a plurality of fuel feeding devices for the boiler furnace with means for automatically varying 20 the number of such devices in operation at a given time.

Another object is to provide a plurality of motor driven devices of the above character, with means for insuring operation of 25 certain or all of said devices, in accordance with the demand upon the boiler.

Another object is to provide means for automatically varying the speed of the driving motor upon variation in the number of 30 fuel feeding devices connected therewith, to thereby provide for gradual variation in the rate of fuel supply.

Other objects and advantages of the invention will hereinafter appear.

The accompanying drawing illustrates an 35 embodiment of the invention which will now be described, it being understood that the invention is susceptible of embodiment in other forms without departing from the 40 spirit and scope of my invention as defined in the appended claims.

In the drawing,

Figure 1 is a schematic and diagrammatic 45 view of a device constructed and arranged in accordance with my invention, and

Fig. 2 is an across-the-line diagram of the circuit connections illustrated in Fig. 1.

Referring to Fig. 1, the numerals 5, 6 and 50 7 designate a battery of fuel-feeding devices adapted to supply pulverized fuel to a single boiler furnace (not shown). Said devices may be of a well known construction, and as shown each comprises a receptacle *a* for pulverized fuel, a screw conveyor *b* driven

through worm gearing *c* for carrying the fuel to a blower *d*, from which it is discharged through nozzle *e* into the furnace. Said devices are respectively provided with electromagnetic clutches 8, 9 and 10 which are operable in the manner hereinafter described to connect the same to or disconnect the same from a rotatable shaft 11 driven by a motor, the armature of which is indicated at 12, suitable bevel gearing being provided as shown. Said motor is adapted 60 to have its speed increased or decreased by variation of the amount of resistance included in circuit with the shunt field *f* in the manner hereinafter described. The motor is supplied with energy from a source of 70 direct current, the supply lines being indicated at *L*¹, *L*²; whereas the armature 12 and field *f* are permanently connected at one side thereof to line *L*² by conductor 13. The motor starter may be of a standard 75 form, and as shown the same comprises an electro-responsive main switch 14, an accelerating relay 15, and a vibrating field relay 16.

A remote control push-button station is 80 preferably provided, the same comprising a normally open start button 17 and a normally closed stop button 18. Thus upon closure of start button 17 an energizing circuit is provided for the winding of main switch 14, said circuit extending from line *L*¹, by conductor 19 through the contacts of said button 17, by conductors 20 and 21 through the normally closed contacts of button 18, by conductor 22 through the winding of switch 85 14, and by conductor 23 to line *L*². Switch 14 upon closure thereof provides a maintaining circuit for its winding, said circuit extending from line *L*¹ by conductor 24 through auxiliary contacts 25, by conductors 90 26 and 21 through the contacts of button 18, and thence to line *L*² as previously traced.

Main switch 14 upon closure provides a circuit for the armature of the motor, said circuit extending from line *L*¹ through the pole contacts 14^a of said switch 14, by conductor 27 through the coils 28 and 29 of relay 15 in series, thence by conductor 30 through the lockout coil 31 of relay 16, by conductor 32 through series coil 33 of said 100 relay, by conductor 34 through starting resistance 35, by conductor 36 through the armature 12, and by conductor 13 to line *L*².

The energizing circuit for the shunt coil 37 of relay 16 may be traced from line L¹ by conductor 24 through auxiliary contacts 25 of switch 14, by conductors 26 and 38 through said coil, and by conductor 39 to line L². Due to energization of coils 28 and 29 of relay 15 in the manner aforescribed the normally open contacts 40 of said relay are closed, thus providing a circuit for shunt field f, said circuit extending from line L¹ through main switch 14, by conductors 27 and 41 through said contacts 40, by conductor 42 through field f, and by conductor 13 to line L². Full strength of the field is thus provided for starting, thereby insuring full torque and slow speed operation of the motor. After a predetermined period, during which the initial inrush of current to the motor subsides, the coils 33 and 37 become predominant, thus effecting closure of contacts 43 of relay 16, which short-circuits coil 29 of relay 15, starting resistance 35, and coils 31 and 33 of relay 16. Said last-mentioned circuit may be traced from line L¹ through coil 28, by conductor 44 through contacts 43, and by conductors 45 and 36 through armature 12 to line L². Contacts 40 of relay 15 will thereupon open, thereby subjecting the circuit of shunt field f to control by a rheostat R. The circuit thus provided may be traced from line L¹ through main switch 14, by conductors 27, 46 and 47, through a contact segment 48 and contact arm 49 of the rheostat to a point in the resistance sections r¹, r² or r³ corresponding with the angular position of arm 49, thence through the resistance by conductor 50 to conductor 42, and through field f to line L².

With contact arm 49 positioned as illustrated in the drawing, obviously none of the resistance will be included in the field circuit, and it may be assumed that under such conditions the motor is adapted to operate at a speed of 700 R. P. M.; whereas with maximum resistance in the field circuit the motor is adapted to operate at a speed of 2100 R. P. M. Rheostat R is also provided with a plurality of auxiliary contact segments 51, 52 and 53 adapted to be engaged by contact arm 54 for control of relays R¹ and R² in the manner now to be described. Contact arms 49 and 54 are formed integrally or otherwise electrically connected, whereby in the position illustrated an energizing circuit is provided for the winding of relay R², said circuit extending from line L¹ through the contacts 14^a of main switch 14, by conductors 27, 46 and 47 to segment 48, through contact arms 49 and 54, to segment 51, by conductor 55 through normally closed auxiliary contacts 56 on relay R¹, by conductors 57 and 58 through the winding of relay R², and by conductors 59 and 60 to line L². Relay R² thereupon closes and through the left-hand contacts w thereof

completes an energizing circuit for the winding of electromagnetic clutch 9. Said circuit extends from line L¹ to conductor 46 as previously traced by conductor 61 through the left-hand contracts w of relay R², by conductor 62 through the winding of clutch 9 and by conductors 63, 64 and 65 to line L². Clutch 9 thereupon acts to connect the fuel-feeding device 6, through suitable gearing, to the drive shaft 11 of the motor. 75

In the particular installation herein disclosed each of the fuel feeding devices 5, 6 and 7 is adapted to supply pulverized fuel at rates ranging from 8 1/3 pounds per minute, when the motor is operating at the minimum speed of 700 R. P. M., to 25 pounds per minute, when the motor is operating at the maximum speed of 2100 R. P. M. I have therefore provided cooperating clutch control and speed control means whereby the rate of fuel supply to the boiler furnace may be varied from 8 1/3 pounds per minute to 75 pounds per minute. Moreover, I have provided means whereby the rate of fuel supply is automatically varied in accordance with the demand upon the boiler. Said means may comprise a lever 66 pivoted at 67 and operable by means of an expansible member 68 subjected, as by pipe 69, to the steam pressure of the boiler. Pivottally connected to one end of lever 66 is a rod 70 carrying a pair of spaced pistons or blocks 71 and 72 adapted to slide within a passageway 73, said blocks acting, in the position illustrated, to jointly close passages 74 and 75 leading to the lower and upper sides, respectively, of a piston 76 operating in a cylinder 77. Leading into the passageway 73 intermediate said blocks 71 and 72 is a conduit 78 connected with any suitable source of fluid under substantially constant pressure. Thus assuming movement of blocks 71 and 72 upwardly by the means aforescribed fluid under pressure will pass through conduit 78, passageway 73 and conduit 75 to the chamber above piston 76, thus tending to force the latter downwardly; whereas obviously the chamber beneath piston 76 will be in communication, through passage 74 and chamber 79, with exhaust or outlet 80. Such downward movement of piston 76 and the attached rod 81 will, through suitable rack and pinion gearing 82, 83, effect counterclockwise movement of contact arms 49 and 54 of the rheostat. Similarly, upon downward movement of blocks 71 and 72, conduit 78 will be thrown into communication with the chamber beneath piston 76, through passageway 73 and conduit 74, whereas the chamber above said piston will communicate with outlet 84, through chamber 85 and conduit 75. The blocks 71 and 72 are adapted to move upwardly under the action of the weight 86 carried by lever 66 when the amount of steam generated is insufficient to meet the demand 130

upon the boiler, and as aforescribed the arms 49 and 54 are automatically moved in a counterclockwise direction to increase the supply of fuel to the boiler furnace; whereas 5 if the amount of steam generated exceeds the demand, blocks 71 and 72 are moved downwardly to effect clockwise movement of arms 49 and 54 thus decreasing the rate of fuel supply.

- 10 Referring again to the rheostat R, it will be noted that upon counterclockwise movement of arm 54 the latter is adapted to engage segment 52 just prior to disengagement thereof from segment 51, so that relay R¹ is 15 energized and closed to bring in clutches 8 and 10 substantially simultaneously with de-energization of relay R², which opens to drop out clutch 9. At the same time contact arm 49 will be in engagement with contact 87 of 20 the rheostat, so that upon closure of relay R¹ a portion of the resistance previously included in the circuit of field f will be short-circuited to temporarily reduce the speed of the motor. Said short-circuit may be traced 25 from contact 87, by conductor 88 through the left-hand contacts z of relay R¹, by conductor 89 to an adjustable contactor 90. The aforescribed short-circuit will be effective during continued closure of relay R¹, where- 30 as upon continued movement of arms 49 and 54 in a counterclockwise direction the resistance in section r² is gradually included in the field circuit to increase the motor speed, with consequent increase in the amount of 35 fuel supplied by devices 5 and 7, until arm 49 is in engagement with contact 91, at which time arm 54 will be in engagement with segment 53, thus providing an energizing circuit for the winding of relay R² shunt- 40 ing the auxiliary contacts 56 of relay R¹, which contacts are then in open position. Said energizing circuit, which extends by 45 conductors 92 and 58 through the winding of relay R², will be obvious. Upon reclosure of relay R² the winding of clutch 9 will be en- 50 ergized,—the energizing circuit being completed through closure of the left-hand contacts w of said relay, as aforescribed. Closure of the right-hand contacts x of said 55 relay effects short-circuiting of a portion of the resistance section r², said short-circuit ex- 60 tending from contact 91, by conductor 93 through said right-hand contacts x, by conductor 94 to adjustable contactor 95. All of 65 the fuel feeding devices 5, 6 and 7 will now be connected to the driving motor, with the speed of the latter temporarily reduced to an extent such that the rate of fuel supply of said devices jointly will be substantially equal 70 to or slightly in excess of the maximum rate of supply when devices 5 and 7 only were in operation. Thereafter upon continued movement of arm 49 in a counterclockwise direction the field f is weakened by gradual 75 inclusion of the steps of resistance in section

r³, until the motor is operating at the maximum speed (2100 R. P. M.) with all of the devices 5, 6 and 7 connected thereto.

By suitably arranging and calibrating the resistance sections r¹, r² and r³ and the segments 51, 52 and 53 for varying the number of fuel-feeding devices connected to the motor drive I am enabled to vary the rate of fuel supply through the wide range aforesigned; whereas the arrangement is preferably such that a uniform change in the rate of fuel supply is effected upon each unit of travel of the rheostat arms 49 and 54. Obviously upon a decrease in the demand upon the boiler the control elements are operated 80 in the reverse direction to automatically and proportionately decrease the rate of fuel supply.

Operation of the electrical control elements will now be described in connection 85 with the line diagram of Fig. 2. Thus assuming momentary closure of push-button switch 17 an energizing circuit for the winding of main switch 14 is provided, said circuit extending from line L¹ through switch 17 and normally closed stop push-button switch 18 through said winding to line L²; a parallel energizing circuit for winding 37 of relay 16 being also provided. Upon closure of switch 14 a circuit for armature 12 of 90 the motor is completed, said circuit extending from line L¹ through the pole contacts 14^a of switch 14, thence in series through windings 28 and 29 of relay 15, windings 31 and 33 of relay 16 and through starting resistance 35 and armature 12 to line L². Auxiliary contacts 25 upon closure thereof provide 95 maintaining circuits for the winding of switch 14 and the winding 37 of relay 16, said circuits being obvious. 100

Energization of windings 28 and 29 ini- 105 tially effects closure of contacts 40 of relay 15 thereby shunting all of resistance sections r¹, r² and r³, and connecting the field f di- 110 rectly across lines L¹, L², whereby full field strength is insured for starting. Upon completion of the starting period the degree of energization of winding 31 is decreased, whereupon windings 33 and 37 cooperate in 115 a well known manner to effect closure of contacts 43 of relay 16, thereby short-circuiting winding 29 of relay 15 and windings 31 and 33 of relay 16; contacts 43 being held in closed position due to continued energization of winding 37. Upon short-circuiting of 120 winding 29 the winding 28 becomes incapable of holding relay 15 in closed position, and upon opening of the contacts 40 thereof the amount of resistance included in circuit with field f is dependent upon the position of 125 rheostat arm 49. Thus assuming a minimum demand upon the boiler, arm 49 will be in the position illustrated wherein the motor is subjected to full field strength; and it may be assumed that under such conditions the mo- 130

tor will operate at a speed of 700 R. P. M. Moreover, under these conditions the winding of relay R^2 will be energized by a circuit extending from line L^1 through the main switch contacts 14^a, thence to segment 48, rheostat arm 54, to segment 51, and through normally closed auxiliary contacts 56 of relay R^1 through said winding to line L^2 . Upon closure of relay R^2 the left-hand contacts w thereof complete an energizing circuit for the winding of clutch 9, said circuit being obvious. The fuel feeding device is therefore driven by the motor, and at the motor speed aforementioned said device may be assumed to be supplying fuel at the rate of $8\frac{1}{3}$ pounds per minute. If the demand upon the boiler increases the arm 49 is gradually moved to the left to include steps of resistance section r^1 in circuit with field f until the contact 87 is reached, at which point the motor may be assumed to be operating at a speed of 1750 R. P. M., with device 6 supplying fuel at the rate of about 21 pounds per minute.

If the demand upon the boiler increases further arms 49 and 54 will continue to move gradually to a corresponding degree, whereas prior to inclusion of any of the steps of resistance in section r^2 by arm 49, arm 54 will move into engagement with segment 52 to complete an energizing circuit for the winding of relay R^1 , whereas arm 54 will be simultaneously moved out of engagement with segment 51, thus interrupting the energizing circuit of relay R^2 and the drive of device 6. Closure of relay R^1 through its right-hand contacts y completes an energizing circuit for the clutch windings 8 and 10 in parallel, thereby connecting fuel feeding devices 5 and 7 to the motor drive. Also upon closure of the left-hand contacts z of relay R^1 a portion of the resistance section r^1 will be short-circuited, the strength of field f being in this manner sufficiently increased to reduce the motor speed to about 925 R. P. M., at which speed of the motor the devices 5 and 7 will jointly supply fuel at the rate of about 22 pounds per minute.

Upon continued movement of arm 49 the steps of resistance section r^2 will be gradually included until the contact 91 is reached,—at which point the motor speed may be assumed to be about 1600 R. P. M., at which speed of the motor the devices 5 and 7 will jointly supply fuel at the rate of 38 pounds per minute. Upon continued movement of arms 54 and 49 the former will come into engagement with segment 53 to provide an energizing circuit for the winding of relay R^2 independently of auxiliary contacts 56 of relay R^1 , whereas relay R^2 in closing short-circuits a portion of resistance section r^2 , through the right-hand contacts w thereof. The field f will thus be again temporarily strengthened to provide a motor speed

of about 1100 R. P. M. with all of the devices 5, 6 and 7 connected thereto, and jointly supplying fuel at the rate of about 39 pounds per minute. Movement of arm 49 may continue until all of the resistance section r^2 as well as the non-short-circuited portions of resistance sections r^2 and r^1 are included in the field circuit, at which time the maximum speed of the motor (2100 R. P. M.) is attained. The devices 5, 6 and 7 will then be jointly supplying fuel at the rate of 75 pounds per minute. If necessary or desirable a suitable stop may be provided for limiting travel of the arms 49 and 54 in a counterclockwise direction. The manner of operation of the system in a reverse direction to decrease the rate of fuel supply due to a decrease in the demand upon the boiler is believed to be obvious without further description.

It will be noted that when conditions are such that the fuel demand may be supplied by a single feeder the fuel is supplied through the nozzle of the middle device 6, whereas when two feeders are required the fuel is supplied through the nozzles of the end feeders 5 and 7. In this manner better combustion conditions in the furnace are obtained; but it is to be understood that the mode of operation of the system in this respect may be modified if desired.

While I have shown the present device as applied to the control of the fuel supply to a single boiler furnace, it is to be understood that the same is equally applicable to the control of a plurality of boilers adapted to jointly supply a common demand. In such an installation certain of the boiler fuel feeding control devices would be set to provide a constant rate of fuel supply, whereas other of such devices would be operative as herein described to accommodate variations in the steam demand upon the boilers jointly. Moreover, the arrangement would be such that the boiler fuel feeding controllers could alternatively be connected for variation of the fuel supply, whereby different boilers would be adapted to accommodate the variable steam demand upon the boilers jointly.

What I claim and desire to secure by Letters Patent is:

1. In a controller for fuel feeding devices, the combination with a plurality of fuel feeding elements, of common driving means for said elements, means for automatically varying the speed of said driving means, and means for automatically varying the number of said elements connected with said driving means in accordance with the fuel demand of the service being supplied thereby.

2. In a fuel feed controller for boiler furnaces, the combination with a plurality of fuel feeding elements, of a common driving motor therefor, means for sequentially in-

- creasing or decreasing the number of fuel feeding elements connected with said motor, and means for gradually varying the speed of said motor to thereby vary the amount 5 of fuel supplied by said elements, said means including means for abruptly varying the speed of said motor upon an increase or decrease in the number of said elements connected therewith to thereby provide for 10 gradual variation of the amount of fuel supplied by said elements throughout the total range of supply thereof.
3. In a fuel feed controller for boiler furnaces, the combination with a plurality of 15 fuel feeding elements, of a common driving motor therefor, means for sequentially increasing or decreasing the number of fuel feeding elements connected with said motor, means for gradually varying the speed of 20 said motor to thereby vary the amount of fuel supplied by said elements, said means including means for abruptly varying the speed of said motor upon an increase or decrease in the number of said elements connected therewith to thereby provide for 25 gradual variation of the amount of fuel supplied by said elements throughout the total range of supply thereof, and means for sub- 30 jecting said speed varying means to control in accordance with pressure conditions in the boiler.
4. In a fuel feeding device, the combination with a plurality of fuel feeding elements, of a common drive for said elements, 35 means for connecting one of said elements with said drive, means operable automatically in response to variations in the fuel demand for gradually varying the rate of operation of said element, and means operable 40 automatically for thereafter disconnecting said element from said drive and simultaneously connecting other of said elements with the latter.
5. In a fuel feeding device, the combination 45 with a plurality of fuel feeding elements, of a common drive for said elements, means for connecting one of said elements with said drive, means operable automatically in response to variations in the fuel 50 demand for gradually varying the rate of operation of said element, and means operable automatically to thereafter disconnect said element from said drive and to simultaneously connect other of said elements with the latter, said last mentioned means being also operable automatically to thereafter re- 55 connect said first mentioned element with said drive.
6. In a fuel feeding device, the combination 60 with a plurality of fuel feeding elements, of a common driving motor for said elements, means for connecting one of said elements with said motor, means for automatically varying the speed of said motor 65 through a given range to thereby vary the amount of fuel supplied by said element, means for thereafter automatically disconnecting said element from said motor and simultaneously connecting other of said elements with the latter, and means for insuring a predetermined decrease in the speed of said motor upon connection of said last-mentioned elements therewith. 70
7. In a fuel feeding device, the combination with a plurality of fuel feeding elements, of a common driving motor for said elements, means for connecting one of said elements with said motor to be driven thereby, means for gradually increasing the speed of said motor through a predetermined range 75 to provide for increasing the amount of fuel supplied by said element, means for interrupting the operation of said element when a predetermined rate of supply thereof has been attained, and means for simultaneously connecting a plurality of the other of said elements with said motor to be driven thereby under conditions of temporarily reduced speed of the latter, whereby the initial rate of supply of said last-mentioned elements 80 jointly is substantially equal to the aforementioned rate of supply of said first-mentioned element. 85
8. In a fuel feeding device, the combination with a plurality of fuel feeding elements, of a common driving motor for said elements, means for connecting one of said elements with said motor to be driven thereby, means for gradually increasing the speed of said motor through a predetermined 90 range to provide for increasing the amount of fuel supplied by said element, means for interrupting the operation of said element when a predetermined rate of supply thereof has been attained, means for simultaneously 95 connecting a plurality of the other of said elements with said motor to be driven thereby under conditions of temporarily reduced speed of the latter, whereby the initial rate of supply of said last-mentioned elements 100 jointly is substantially equal to the aforementioned rate of supply of said first-mentioned element. 105
9. In a fuel feeding device, the combination with a plurality of fuel feeding elements, of a common driving motor for said elements, means for connecting one of said elements with said motor to be driven thereby, means for gradually increasing the speed of said motor through a predetermined 110 range to provide for increasing the amount of fuel supplied by said element, means for interrupting the operation of said element when a predetermined rate of supply thereof has been attained, means for simultaneously connecting a plurality of the other of said elements with said motor to be driven thereby under conditions of temporarily reduced speed of the latter, whereby the initial rate of supply of said last-mentioned elements 115 jointly is substantially equal to the aforementioned rate of supply of said first-mentioned element, means for gradually increasing the speed of said motor until a predetermined rate of supply of said second-mentioned elements has been attained, and means for thereafter reconnecting said first-mentioned element under conditions of temporarily reduced speed of the motor, whereby the initial rate of supply of all of said elements 120 jointly is substantially equal to the aforementioned rate of supply of said second-mentioned elements. 125

range to increase the amount of fuel supplied by said element, means for interrupting the operation of said element when a predetermined rate of supply thereof has been attained, means for simultaneously connecting a plurality of other of said elements with said motor to be driven thereby under conditions of temporarily reduced speed of the latter, whereby the initial rate of supply of said last-mentioned elements jointly is substantially equal to the aforementioned rate of supply of said first-mentioned element, means for gradually increasing the speed of said motor until a predetermined rate of supply of said second-mentioned elements has been attained, means for thereafter reconnecting said first mentioned element under conditions of temporarily reduced speed of the motor, whereby the initial rate of supply of all of said elements jointly is substantially equal to the aforementioned rate of supply of said second-mentioned elements, and means for gradually increasing the speed of said motor until the maximum rate of supply of all of said elements jointly has been attained.

10. In a controller for pulverized fuel feeding systems for steam boilers, the combination with a plurality of devices for supplying the fuel under pneumatic pressure, electromagnetic clutches for connecting said devices with a common driving motor, electromagnetic relays for controlling said clutches selectively, circuit commutating means for controlling the operation of said relays, and means responsive to boiler pressure conditions for controlling the operation of said commutating means.

11. In a controller for pulverized fuel feeding systems for steam boilers, the combination with a plurality of devices for supplying the fuel under pneumatic pressure, electromagnetic clutches for connecting said devices with a common driving motor, electromagnetic relays for controlling said clutches selectively, circuit commutating means for controlling the operation of said relays, and means responsive to boiler con-

ditions for controlling the operation of said commutating means, said commutating means including means for automatically varying the speed of said motor.

12. The combination with a plurality of material handling elements, of a direct current motor comprising an armature and a shunt field for driving said elements, resistance to be included in or excluded from the circuit of said field to vary the speed of said motor, electromagnetic clutches for connecting said elements to said motor to be driven thereby, electromagnetic relays for controlling operation of said clutches, circuit commutating means for controlling operation of said relays, said means including means for gradually varying the amount of resistance in circuit with said field upon connection of one or more of said elements to said motor, and interlocking means between said relays and said commutating means to provide for abrupt variation in the amount of resistance in circuit with said field upon variation in the number of elements connected to said motor.

13. In a control system, in combination, a plurality of driven devices, common driving means therefor, and means operable automatically to vary the number of said devices connected with said driving means, said second mentioned means including means to simultaneously vary the speed of said driving means.

14. In a control system, in combination, a common driving motor, a plurality of devices to be jointly or severally connected therewith to be driven thereby, and means operable automatically for gradually varying the speed of said motor during connection of certain or all of said devices therewith, said means being also operable automatically to abruptly vary the speed of said motor upon variation in the number of devices connected therewith.

In witness whereof, I have hereunto subscribed my name.

RALPH G. LOCKETT.
